(57) **CLAIM**

The ornamental design for a bidirectional dimple core panel, as shown and described.

DESCRIPTION

FIG. 1 is a top front perspective view of a first embodiment of a bidirectional dimple core panel;

FIG. 2 is a top view thereof, the bottom view being identical to the top view;

FIG. 3 is a front view thereof;

FIG. 4 is a sectional view thereof taken along line 4-4 of FIG. 2 thereof;

FIG. 5 is a top front perspective view of a second embodiment of a bidirectional dimple core panel having an appearance the same as the embodiment of FIGS. 1-3 except that the top and bottom sheets of the panel have a stippling representing a first color and the dimpled layers of the dimple core having different stippling representing a second color different from the first color;

FIG. 6 is a front view of the panel of FIG. 5;

FIG. 7 is a top front perspective view of a third embodiment of a bidirectional dimple core panel having an appearance the same as the embodiment of FIGS. 1-3 except that a top sheet of the panel and lower dimpled layer of the dimple

core have a stippling representing a first color and a bottom sheet of the panel and upper dimpled layer of the dimple core have a different stippling representing a second color different than the first color;

FIG. 8 is a front view of the panel of FIG. 7;

FIG. 9 is a top front perspective view of a fourth embodiment of a bidirectional dimple core panel having an appearance the same as the embodiment of FIGS. 1-3 except that a top sheet of the panel and an upper dimpled layer of the dimple core having a stippling representing a first color and a bottom sheet of the panel and lower dimpled layer of the dimple core have a different stippling representing a second color different than the first color;

FIG. 10 is a front view of the panel of FIG. 9;

FIG. 11 is a top front perspective view of a fifth embodiment of a bidirectional dimple core panel having an appearance the same as the embodiment of FIGS. 1-3 except that a top sheet of the panel has a stippling representing a first color and a bottom sheet of the panel and dimpled layers of the

dimple core have a different stippling representing a second color different than the first color;

FIG. 12 is a front view of the panel of FIG. 11;

FIG. 13 is a top front perspective view of a sixth embodiment of a bidirectional dimple core panel having an appearance the same as the embodiment of FIGS. 1-3 except that a top sheet of the panel has a stippling representing a first color, an upper dimpled layer of the dimple core has a stippling representing a second color, a lower dimpled layer of the dimple core has a stippling representing a third color, and a bottom sheet of the panel has a stippling representing a fourth color, at least one of the first, second, third and fourth colors being different from the others; and,

FIG. 14 is a front view of the panel of FIG. 13.

The rear views of each embodiment form no part of the claimed design.

The broken lines define the boundaries of the claimed design and form no part thereof.
